(57) **CLAIM**

The ornamental design for an adjustable bed frame, as shown and described.

DESCRIPTION

FIG. 1 is a top plan view of an adjustable bed frame according to my design in a first retracted state;

FIG. 2 is a bottom plan view thereof;

FIG. 3 is a front elevation view thereof;

FIG. 4 is a left side view thereof;

FIG. 5 is a right side view thereof;

FIG. 6 is a top, right, front perspective view thereof;

FIG. 7 is a top plan view thereof in an extended state;

FIG. 8 is a bottom plan view thereof; and,

FIG. 9 is a front elevation view thereof.

The broken lines shown in the figures illustrate portions of the adjustable bed frame that form no part of the claimed design.
